[57] CLAIM

The ornamental design for a cap-shaped slipper, as shown and described.

DESCRIPTION

FIG. 1 is a front perspective view of a cap-shaped slipper embodying my new design;

FIG. 2 is a rear perspective view of a cap-shaped slipper embodying my new design;

FIG. 3 is a front view thereof;

FIG. 4 is a rear view thereof;

FIG. 5 is a side view thereof, the other side view being mirror image thereof;

FIG. 6 is a top view thereof; and,

FIG. 7 is a bottom view thereof.

The broken line showing of the slipper bottom in the Figures is for illustrative purposes only and forms no part of the claimed design.
